UNITED STATES PATENT OFFICE.

EMANUEL W. DUNN, OF SAN FRANCISCO, CALIFORNIA.

OIL-BURNING SYSTEM.

1,110,119.

Specification of Letters Patent.

Patented Sept. 8, 1914.

Application filed February 8, 1912. Serial No. 676,343.

To all whom it may concern:

Be it known that I, EMANUEL W. DUNN, a citizen of the United States, residing in the city and county of San Francisco and State of California, have invented new and useful Improvements in Oil-Burning Systems, of which the following is a specification.

This invention relates to a system for the control and combustion of hydrocarbons.

It is one of the objects of the present invention to provide a system for the control and combustion of hydrocarbons, in which there is arranged a combination of elements all coöperative to produce the maximum heating efficiency due to combustion of the oil; to provide an oil handling system designed to produce a mixture of hydrocarbon and steam, and air, if desired, for the purpose of producing an inflammable gas, means being provided to control to a nicety the volume and the pressure of the oil to be burned, and means being provided to control the admission and pressure of the steam or other fluid which may be utilized in aiding combustion by vaporizing the oil.

It is also an object of the invention to provide in combination in a system for feeding and consuming hydrocarbons means whereby the pressure of the steam employed to force the hydrocarbon or oil through the apparatus is automatically controlled by the pressure of the oil discharged by the pump; to provide means whereby a portion of the steam, which may be used for the vaporization of the oil, may be used to preliminarily heat the oil before it is admitted to the mixing chamber and to heat air; and to provide means whereby the steam utilized in the heater is also conducted to and used in the mixer, a suitable pressure regulating medium being introduced in the system to control the pressure of the steam or the air used for heating and vaporizing the oil.

A further object of the invention is to provide in combination with the system a reservoir or tank of suitable design and location wherein may be safely contained the oil handled in the system, and which is so connected in the system that the former may be drained of water or sediment, as necessary, by a pump employed in the system; means being also provided whereby the fluid may be admitted under pressure to scavenge and cleanse the tank.

The invention consists of the parts and the construction and combination of parts as hereinafter more fully described and claimed, having reference to the accompanying drawings, in which—

Figure 1 is a general view of the apparatus in partial section. Fig. 2 is a detailed view of the mixing valve. Fig. 3 is a section on line X—X, Fig. 2. Fig. 4 is a view of the spray tip detached. Fig. 5 is an enlarged vertical section of one of the pressure regulators.

In its illustrated embodiment the system comprising my invention includes a tank, 70 reservoir or other container A located in suitable position, which position is now frequently determined by municipal ordinances for the safety of the building in connection with which oil burning systems may be 75 used. It is one of the particular features of the present invention that when the oil tank A is of necessity located below the ground or at some distant point from the general plant, the tank may be cleansed or 80 drained at necessary times without requiring the attention of a person immediately at the tank.

To that end the tank is connected to a suitable pump B by a suction pipe 2, which 85 extends well toward the bottom of the tank, which may be formed of a depressed portion 3 wherein will naturally collect heavier particles of sediment and water, which occasionally is contained in the oil. The pipe 90 2 is connected to the pump B and in the connection I provide a valve 4 which may be closed to prevent the suction of water, etc., through the pipe 2 by the pump when the latter is in operation.

Under normal conditions oil is drawn from the tank A through a suction pipe 5 which extends down into the tank a suitable depth and preferably terminates at a point considerably above the bottom of the 100 tank, and in the suction pipe 5 is a valve 6 which may be closed when the valve 4 of the suction pipe 2 is opened. During the normal operation of the plant the suction pipe is closed by its valve 4 and the oil suction 105 pipe 5 is opened to communication with the pump by opening valve 6. Then, when the pump is running, a volume of comparatively pure oil will be drawn from the tank through the pipe 5.

Steam to drive the pump B is derived from a boiler C, to which the present system

is shown connected, so that the oil pumped through the system, when burned in the furnace of the boiler, produces steam, a portion of which steam is delivered from the 5 boiler C through a main pipe 7 provided with branches 8—9, the former having a valve 10 connected to a pressure controlling device, indicated at 11, from which the steam will pass to the pump through a connection 12 having a valve 13, whereby the 10 operation of the pump may be controlled.

A branch 14 may be connected to the steam pipe 12, so that steam may be conducted into 15 a washer or spray head 15 in the tank. When steam or other fluid is turned into the 20 spray head 15, this will thoroughly scavenge or cleanse the tank A, while the sediment may be drawn from the tank by the pump through the suction pipe 2 when the valves are properly adjusted.

When the pump B is operating and drawing oil through the pipe 5, the oil is discharged by the pump into a feed pipe 16, in which is a valve 18. The valve 18 in the oil 25 pipe 16 is normally open when the pump is operating, or the oil and the liquid is delivered through the feed pipe 16 into a suitable form of mixing and heating chamber D, from which it passes in a vaporized condition into a burner E. The valve 18 is 30 closed to cut off the oil pipe 16 when the pump is running to draw water or residue material from the bottom of the tank; a connection 17 delivering the refuse or 35 drained material to a pipe 19, in which is a valve 20 normally closed during the pumping of oil through feed pipe 16.

The branch 9 from the main steam pipe 7 connects to a pressure regulator 21 from 40 which extends a low pressure branch 22 in which is mounted a valve 23; the latter being connected by a pipe 24 to heater D, to which is connected the oil feed pipe 16. The steam, which is utilized, in part, to raise 45 the temperature of the oil as it passes through the heater D, will then pass immediately from the heater into burner E.

It may be sometimes, and frequently is, 50 desirable to very materially increase the temperature of the steam which is delivered to the heater D, and for that purpose I connect to the pipe 24 a superheating branch 27, which extends into the firebox of the furnace, as shown, and returns to, and is connected with the pipe 24 below the valve 23. The superheating branch 27 is provided with 55 suitable controlling valves 28, so that the flow of steam through the branch may be controlled or cut out, as desired.

One of the important purposes of the 60 superheating branch 27 is to first raise the temperature of the oil from pipe 16 in the mixer D, so as to materially decrease the density or increase the fluidity of the oil, 65 and also, by increasing the temperature of

the steam, its vaporizing effect upon the oil in the mixer is gradually increased. This superheating of the steam, as provided in the present system, is very valuable in the handling of certain oils, it being well known that the specific gravity and viscosity of oil vary greatly, and the maximum heating efficiency of these various grades of oil can only be produced in a system capable of the various adjustments of the temperature and pressure of the steam and oil being handled. It is to that end that the present system is provided with elements conducive of the desired result.

One of the particular features of the 90 present invention is in so organizing the system that the pressure of the steam operative upon the pump B may be controlled at all times automatically by the pressure of the liquid fuel discharged by 95 the pump. In the present instance this automatic control is accomplished by connecting, to the pump B a pipe or connection 30, in which may be mounted a pressure gage 31; the pipe 30 being connected to the pressure 100 regulator 11 which may be of suitable construction and which is adapted to operate for the control of the steam passing through the branch 8 to the pump B.

The pressure regulator 11 may be so adjusted that the pump will be operated by the pressure of steam designed to discharge from the pump oil having a given pressure, and once the regulator 11 is set to produce a given relation of pressures between the pressure of the steam driving the pump and the pressure of the oil delivering from the pump, the latter pressure will at all times automatically control the pressure delivered to the pump through the pipe 12 by means of the regulator 11, to which the connection 30 is secured. In other words, if a given pressure in the steam pipe 12 will produce a certain pressure of oil in the oil pipe 16, and the regulator 11 is set to maintain 110 constantly the ratio of proportion in the pressures, any increase of pressure in the steam line which will tend to increase the pressure in the pump line 16, will render the increasing pressure of the oil in the line 115 30 effective, through the medium of the pressure regulator 11, to cut down the pressure of the steam in the pipe 12.

It is also desirable to provide in the system means for automatically controlling the 120 pressure of the steam which is utilized in part to heat the oil in the heater D and later to vaporize the oil, and this automatic control of the pressure of the steam used for these purposes is accomplished by connecting to the feed pipe 22 a pipe 32, in which may be mounted a gage 33; the pipe 32 being connected to the pressure regulator 21 in the branch 9. The operation of the regulator 21 in this case is such that, when an in- 130

crease of pressure occurs in the branch pipe 9 and there is a tendency to further increase the pressure in the pipe 24, the latter increase will automatically effect the pressure 5 regulator 21 to cut down the pressure passing through from the pipe 9; thus at all times maintaining a given or fixed pressure in the steam utilized in the mixer D.

It will thus be seen that I have combined 10 in my oil handling system means for automatically controlling the pressure of the oil delivered to the burner E and means for automatically controlling the pressure of the steam utilized to vaporize the oil.

15 The invention illustrated discloses means whereby the oil and steam may be admitted simultaneously to the mixer D, at normal temperature of the steam coming from the main pipe 7, or, if desired, the temperature 20 of the steam before being admitted to the mixer D may be increased by the direction of the steam through the superheater 27, and from which it is delivered into the heater D for proportionately increasing the 25 temperature of the oil from the feed pipe 16, so that both the temperature of the steam and the oil is increased simultaneously when the superheater 27 is connected up.

One of the objects of providing independent, 30 separately operable pressure regulators, as 11-21, is to provide for the separate control of pressure of oil in the feed pipe 16 and the separate control of the pressure in the atomizing steam coming through feed 35 pipe 24; the object of the independent control being to maintain the pressure of oil in the feed pipe 16 slightly in excess of that of the mixing steam in the pipe 24, to prevent the excess pressure of steam, should it exist, 40 from forcing the oil backwardly from the mixer D.

Having provided an organization of parts 45 coöperative to produce a mechanism efficient for the combustion of hydrocarbons, it is also necessary to employ means whereby the proportions of the oil, air and steam, as to their volumes, may be nicely determined for the better operation of the system, which includes means for the refined determination 50 of the volume of the oil and steam; and I have found that good results are obtained when the volumes of oil and steam are so controlled. To accomplish this control, I employ a mixer or valve, as D, including a 55 casing provided with a bore in which is movable a plug or valve 35, having an upper channel 36, and a lower axial channel 37; the upper end of the valve 35 connecting with the oil feed pipe 16 and the lower end 60 of the valve 35 connecting with the steam feed pipe 26. The channel 36 of the valve 35 communicates with an oil duct 38 in the casing of the mixer D, by means of one or the other of a plurality of differently sized 65 radial openings, as 39-39'-39".

The lower axial duct 37, into which steam may be admitted, communicates with a discharge chamber 40 in the mixer D through one or the other of a series of radial, differently sized ports 41-41'-41". The ports 70 39-41, 39'-41', and 39"-41" are preferably arranged in a common line longitudinally in the valve 35 and each set of the ports, as designated, for instance, 39-41, is positioned according to its size; in this instance, 75 the ports 39-41 being the smallest in the series, and when turned to register with the respective channels 38-40 in the mixer, a proportionate volume of steam and oil will be admitted into the mixing chamber 43 of 80 the mixer. Since the ports 39-41 are the smallest in their respective series, the smallest volume of oil and steam will be delivered into the mixer, and if a larger volume of each is desired, the valve 35 is 85 turned by its handle 35" to bring the next larger set of openings, as 39'-41" into registration with the channels 38-40. Thus there may be always introduced in the mixer D a given or fixed proportion of oil and steam; the latter being constantly and automatically subjected to similar or different pressures, as determined by the adjustment of the pressure controlling devices 11-21.

The necessity in a system of this kind for 95 the provision of a valve permitting the inlet of fixed proportions of steam and oil is apparent because of the variations in the quality of oils and also by reason of the variations permitted in the pressure of the oil 100 and steam by the system provided; the maximum heating values of the oil being derived only when the proper degree of pressure and the proper proportions of steam and oil can be obtained, with the proper volume of air. 105

In cold climates it is desirable to apply heat to the hydrocarbon or oil in the tank A, so that it can be drawn with more facility into the suction pipe 5, Fig. 1. In this instance I have shown the suction pipe 5 as 110 surrounded by a heating cylinder 5' connected to the steam pipe 14, from which sufficient steam may be admitted to the heater 5' to heat the oil immediately adjacent the suction pipe 5, thus aiding in its flow 115 through the pipe, a small quantity of steam being sufficient for the purpose.

A suitable form of door or gate 46 is shown at the furnace, which may be regulated to admit a proper volume of air thereto. In order to keep the infeeding oil heated as it passes the mixer D, the superheater is located close to the mixer. As many branches of oil feeders as desired may be led from the feed pipe 16; one branch 16' 120 being indicated and having a pressure reducer 16" for lowering the pressure in the branch 16'.

Fig. 2 is a detail of the heater and mixer D, to the bottom of which is attached the 130

steam pipe 26, the oil pipe 16, and an air supply pipe 50. The oil flows through a central duct 51 to the port 36 of the valve plug, the steam enters a chamber 52 around the duct 51, thus heating the oil, and the air from pipe 50 enters a chamber 53, thus also being heated by the steam.

When desired, air may be directed into the channel 37 of the valve by removing a plug 54 from the heater D, Fig. 3, opening a port 55, leading to the valve channel 37. By placing plug 54 in the steam duct 52, steam is stopped from flowing to valve 35 while air is admitted, a plug, 54^a and the plug 54 being transposed.

By the peculiar construction of the heater D the oil is heated to the desired temperature right at the burner by the steam in chamber 52, thus with oil having a temperature by which its viscosity can be controlled; with steam and oil at given pressures, and by means of the proportioning valve 35, a most perfect control of fuel and flame is obtained. If desired, air may be turned into valve 35 in lieu of steam by changing position of the plug 54.

The air pipe 50 is provided with an automatic controlling valve 55, by which pressure of air admitted to the heater and mixer D is nicely determined, as may be required.

Oil may be discharged through one of the openings, as 39' of the valve, without mixing with a vaporizing medium, by cutting off flow of the latter and inserting a tip or nozzle 60, Fig. 4, in the heater D to cut off the flow to chamber 40, so that oil under pressure forced through the valve 35 will issue from the tip 60 in a small thread or jet and be readily combustible. By varying pressure in the oil supply pipe 16, the flame can be controlled independently of the valve 35.

Having thus described my invention, what

I claim and desire to secure by Letters Patent is—

1. The combination in an oil burning, steam generating system, with a boiler, its furnace and a burner therein, of a source of oil supply, a pump connected thereto, and to the burner, apparatus for delivering steam from boiler to pump and burner, regulators in said apparatus for proportioning steam pressures at the pump and at the burner, one of said regulators being controlled by oil discharged from the pump, said apparatus including means for superheating the steam to burner and utilizing the heat to vary the temperature of the oil before entering the burner.

2. The combination in an oil burning system, of an oil burner, an oil supply conductor connected to the burner, a boiler in which steam pressure is generated by combustion at the burner, a pump operated by steam from said boiler, an automatic governor connected to the discharge side of the pump, pipes in which the governor is mounted connecting the boiler and pump, said governor controlling the speed of pump by varying steam supply thereto inversely to oil discharge pressure, connections between the steam supply pipe and the burner, said connection including a chamber surrounding the oil feed conductor whereby the oil is raised in temperature before mixing at the burner tip, and a governor in the steam supply pipe to burner connection whereby the pressure ratio between the oil and steam at the burner is automatically maintained.

In testimony whereof I have hereunto set my hand in the presence of two subscribing witnesses.

EMANUEL W. DUNN.
